(57) **CLAIM**

The ornamental design for a wristband for securing implements, as shown and described.

DESCRIPTION

FIG. 1 is a front view of a wristband in accordance with this invention.

FIG. 2 is a bottom edge view of the wristband of FIG. 1. FIG. 3 is a right side view of the wristband of FIG. 1, wherein the left side view of the wristband is a mirror image of FIG. 3 and therefore not shown; and, FIG. 4 is a rear view of the wristband of FIG. 1.
